BALL DISPENSER FOR GAMES

Fred W. Preece, Toledo, Ohio, assignor to Tri-Putt Company, Toledo, Ohio, a corporation of Delaware

Application April 3, 1940, Serial No. 327,655

9 Claims. (Cl. 312—49)

This invention relates to ball dispensing machines wherein a predetermined number of balls is located in an enclosure, which balls will be dispensed therefrom upon the operation of certain mechanism, preferably coin actuated, and returned thereto after they have served their purpose. While it is to be understood that the number and size of the balls adapted to be received and dispensed by the machine may vary, and that the balls may be used for any desired purpose, the preferred embodiment of my invention as disclosed herein has particular use in conjunction with a putting game apparatus such as disclosed in my issued Patent No. Des. 111,910 under date of October 25, 1938.

It is a particular object of my invention to provide an enclosure having ball receiving means therein adapted to be moved to a ball dispensing position and back again to receiving position.

The device is adapted to be used in conjunction with a coin operated mechanism and, therefore, a further object of the invention is to provide a novel electrical circuit actuated by a deposited coin to cause the ball receiving means to operate through one complete cycle from ball receiving to dispensing position and back again to receiving position.

It is usually advisable to maintain a greater number of balls on hand than will actually be used in the machine and, therefore, a still further object of the invention is to provide a means for preventing entrance of any balls into the enclosure while the ball receiving means is not in receiving position.

To the accomplishment of the foregoing and related ends said invention, then, consists of the means hereinafter fully described and particularly pointed out in the claims.

The annexed drawings and following description set forth in detail certain mechanism and one mode of carrying out my invention, said means constituting, however, but one of various ways in which the principle of the invention may be employed.

In said annexed drawings wherein like reference numerals refer to like parts throughout the various views:

Fig. 1 is a vertical section through the enclosure looking toward the rear thereof and showing some of the operating parts in elevation, and showing the ball receiving means in receiving position.

Fig. 2 is a fragmentary vertical section similar to Fig. 1 but showing the ball receiving means in dispensing position.

Fig. 3 is a vertical section through the enclosure looking toward the right of Fig. 1.

Fig. 4 is a horizontal section through the machine, and

Fig. 5 is a diagrammatic view of the electric circuit and the parts of the machine operated thereby.

In carrying out my invention I provide an enclosure having a bottom 1, a front 2, a back 3, sides 4 and 5, and a top 6. The back 5 is provided with upper and lower openings 7 and 8 respectively, the lower opening 8 providing an entrance into the enclosure for the balls B and the upper opening 7 providing an exit therefor. The passageway provided by the lower inclined member 9 and the upper member 10 may lead to any desired place where the balls are received after they have served their purpose to carry them to the entrance opening 8. At the outer side of the back 5 and adjacent the upper and lower edges of the opening 7 the outwardly extending members 11 and 12 may be located to aid in directing the balls after they have been dispensed through the opening 1 onto a platform or other desired means where they may await use.

Within the enclosure is located a trough 13 having upwardly extending sides thereon adapted to be normally positioned adjacent the lower opening 8, as shown in Fig. 1, and tilted away therefrom so that a plurality of balls entering the lower opening will be received by the trough and held therein. At substantially the center of the trough 13 are secured to the sides thereof the bracket members which are provided with downwardly extending portions 14, horizontal portions 15 and upwardly extending portions 16. Each of the portions 14 is secured to the upwardly extending sides of the trough 13 and the vertical portions 16 are spaced apart sufficiently to receive a link 17 which, at its lower end, is pivotally secured to the portions 16 of the brackets by means of the bolt 18.

A second link 19 is pivotally secured to the upper end of the links 17 for a purpose which will be more fully described hereinafter. Extending between the sides of the enclosure and in the upper portion thereof a shelf 20 is located on which is securely mounted the motor 21 having a shaft 22 extending rearwardly therefrom. The upper end of the link 19 is secured to and rotatable with the shaft 22 so that one complete revolution of the shaft, which will carry the link 19 around with it, will obviously elevate the trough 13 by means of the link 17 to an

upper position and carry it downwardly again to its normal ball receiving position. It will be noted in Fig. 1 that the links 17 and 19 are in their normal position with the trough in its lower position while Fig. 2 discloses these various parts after the shaft 22 has completed one-half of a revolution at which point the trough is in its upper ball dispensing position.

Since the trough 13 must tilt away from the lower opening 8 to receive the balls, it is necessary that it be tilted toward the opening 7 in its upper position so that the balls will naturally roll out through the opening, and to accomplish this result I have provided cam arms secured to the trough, one at each end thereof. The cam arm 23, adjacent the side 5 of the enclosure, is merely a straight rod which is adapted to come against the side 5 when the trough is in its upper position and prevents its being tilted too far. The cam arm 24, adjacent the side 4 of the enclosure, is bent inwardly at an angle near its upper end as at 25 and in the back 3 of the enclosure a screw or pin 26 is provided against which the bent portion 25 of the cam arm 24 is adapted to come as the trough is being elevated. It will be clear that if the trough moves upwardly and the pin strikes the bent portion of the cam rod, that end of the trough will tend to move upwardly into the position shown in Fig. 2 so that when it comes into alignment with the upper opening 7 it will be tilted sufficiently so that the balls will roll out freely. In order to aid in guiding the trough as it nears its normal ball receiving position, additional cam guiding means are provided in the form of blocks 27 which may be located at either or both sides of the enclosure. The rear side of each block 27 is provided at its upper end with a curved portion 28 so that if the trough tends to be out of alignment with the lower opening 8 as it is being moved downwardly, the camming action of the edges of the blocks 27 will force the trough rearwardly to proper position.

I have provided novel means housed within the enclosure so that, upon the depositing of a coin in the slot provided therefor, only one complete revolution of the shaft 22 will take place which will raise the trough to the upper opening 7, dispense the balls, and return the trough to its lower normal ball receiving position where it will remain at rest to receive the balls after they have served their purpose and will not again be moved until another coin has been deposited.

In the detailed description of this mechanism it will be noted that a coin slot 29 is provided by the enclosing guide ways 29a which extends downwardly from the top 6 and will carry a coin 30 deposited therein to a lower position shown in Fig. 3. A solenoid 31 is positioned adjacent the lower end of the coin slot which has an arm 32 extending outwardly therefrom and located immediately below the lower end of the coin slot 29 so that after a coin has been carried downwardly in the slot it will rest on the arm 32 in its lower position. In one side of the enclosure 29a which defines the coin slot and near the bottom thereof is located the arcuate slot 33 which receives therein the lower bent end of the spring arm 34. Arm 34 is pivoted near its upper end by passing through an opening in the lug 35 on a portion of the coin slot enclosure. The upper end of the arm 34, designated at 36, normally acts to spread apart the switch contact members 37. One line of the switch 37 is connected to the motor 21 and the other to the ordinary 110-volt line so that upon the switch being closed, the motor will start a rotation of

the shaft 22. Within the motor housing is located suitable gearing so that the shaft 22 will rotate at a comparatively low speed. The spring arm 34 will normally be in a position where its lower end is at the upper end of the slot 33 so that its upper end 36 acts to maintain the contacts 37 open, but a coin deposited in the slot 29, upon reaching the lower end thereof, will force the spring arm 34 into the position shown in Fig. 3 thereby permitting the contacts 37 to close and initially starting the motor 21.

Also affixed to the shaft 22 is a cam 38 which is provided at its periphery with a high portion 39, a low portion 40 and the intermediate portion 41 which constitutes the greater part of the periphery. Mounted adjacent the cam 38 is a spring arm 42 having its upper end thereof lying against the cam 38 and adapted to follow the contour thereof as it is being rotated. Two switches are mounted adjacent the spring arm 42. The first of these has one contact point on the arm 42 and the other contact point on the spring arm 43. The second switch includes the two spring arms 44 and 45, the first of these being spaced from the arm 42 by the block 46. A contact point is located on each of the arms 44 and 45.

The arm 42 (Fig. 5) is connected to a 110-volt line and its adjacent arm 43 is connected to the motor so that a closing of the switch by contacting the points on these arms will maintain the operation of the motor for one revolution of the shaft 22 even after the switch 37 has been opened. The solenoid 31 has a connection with a 6-volt line and to the switch arm 45, while the other switch arm 46 is also connected to the 6-volt line so that a closing of the contact points on the arms 44 and 45 will energize the solenoid, remove the arm 32 from the path of the coin 30 and permit the coin to drop downwardly to the bottom of the main enclosure. This removal of the coin permits the spring arm 34 to return to its normal position opening the switch 37, but which has no effect on the motor at this stage since the switch contacts on the arms 42 and 43 have been closed.

When the end of the arm 42 is resting on the highest portion 39 of the cam 38 all of the contact points on the arms 42, 43, 44 and 45 will be separated. When the end of the arm 42 rests on the intermediate portion 41 of the cam 38 the contact points on the arms 42 and 43 will be closed to maintain operation of the motor, and when the end of the arm 42 rests on the lowest portion 40 of the cam the contact points on the arms 44 and 45 will also be closed to energize the solenoid 31.

The operation of the machine is as follows:

The device initially, and the mechanism thereof, will be in its normal position as shown in Fig. 1 with the trough 13 in its lower position filled with balls B. The spring arm 34 will have its lower end at the upper end of the arcuate slot 33 maintaining the switch 37 open, and the end of the spring arm 42 will be at rest on the highest portion of the arm 42 on the cam 38. When a coin 30 is dropped into the slot 29 and reaches the lowermost portion thereof where it rests on the arm 32 of the solenoid, it forces the spring arm 34 to the position shown in Fig. 3 where the switch 37 is permitted to close starting the motor 21. As the shaft 22 and the cam 38 thereon rotate in the direction shown by the arrows in the various figures of the drawings, the link 19 through the link 17 will begin to elevate the

trough 13. As soon as the small section of the intermediate portion 41 on the cam 38 is reached by the end of the arm 42 the switch formed by the arms 42 and 43 will be closed to maintain operation of the motor. The end of the arm 42, as the cam continues to rotate, is then positioned momentarily in the lower portion 40 of said cam which closes the switch formed by the arms 44 and 45 thus energizing the solenoid 31 to withdraw the arm 32 thereof permitting the coin 30 to drop to the bottom of the main enclosure. As soon as the coin 30 has left its position against the arm 34, said arm will resume its normal position opening the switch 37 at which time the arm 32 will be moved outwardly to its normal position by reason of the fact that the end of the arm 42 will have reached the larger section of the intermediate portion 41 on the cam 38. In this position of the arm 42 the switch formed by this arm and its adjacent arm 43 will remain closed until the shaft 22 has completed one revolution at which time the end of the arm 42 will again rest on the highest portion of the cam, opening the switch formed by the arms 42 and 43 to stop the motor. During this operation of the circuit, the trough 13 will have been moved upwardly to its position shown in Fig. 2, will remain there long enough to dispense the balls through the opening 7 and be returned to its normal position of Fig. 1.

Usually a greater number of balls is kept on hand than will fill the trough and for this reason it is necessary to provide some means to prevent any of these extra balls from entering the enclosure through the opening 8 during the absence of the trough 13 therefrom. The particular means which I have devised to effect this purpose constitutes a spring arm 47 located beneath the trough 13 and extending longitudinally thereof. One end of the arm 47 is secured to the bottom 1 while the other end has a downturned flange 48 thereon and extends partially into the opening 8. The normal tendency of this arm is to spring upwardly to the dotted line position shown in Fig. 1 but is held down in its full line position by the force of the trough 13. As the trough is moved upwardly, the spring arm 47 also will be raised to the dotted line position of Fig. 1 forcing the extra balls away from the trough where it remains in this position to prevent the entrance of the balls until the trough is returned to its lower position where it forces the spring arm 47 downwardly.

While any desired means may be used to gain access to the enclosure either to remove coins collected therein or for repairs of the mechanism, I have provided the enclosure with a removable front 2 which has a rabbeted portion along its upper edge to fit into a groove in the top section. A plurality of cleats 49 are located along the bottom and sides of the enclosure against which the front 2 may abut when it is in closed position. At the lower edge of the front I provide a space 50 wherein a locking mechanism may be located to lock the enclosure against unauthorized entrance.

From the foregoing disclosure it will be evident that I have provided novel means for receiving and dispensing balls used in conjunction with a game which apparatus has been used successfully in practice and is extremely economical to manufacture and operate.

Other modes of applying the principle of the invention may be employed instead of the one

here explained change being made as regards the mechanism herein disclosed provided, however, that the means stated by any of the following claims or the equivalent of such stated means be employed.

I claim:

1. A ball dispensing machine comprising, a trough to receive a plurality of balls therein and normally in ball receiving position, a link pivotally connected thereto, a rotatable shaft, a second link having one end secured to said shaft and the other end pivotally connected to said first link, whereby one revolution of said shaft will move said trough to ball dispensing position and back to ball receiving position, and means to rotate said shaft one complete revolution.

2. A ball dispensing machine comprising, an enclosure having a front, back and sides, upper and lower openings in one of said sides, a trough within said enclosure to receive a plurality of balls and normally positioned adjacent the lower opening and tilted away therefrom, means to move said trough upwardly to the upper opening and back to the lower opening, and means to tilt said trough toward said upper opening in its upper position to thereby dispense the balls.

3. The combination of elements defined in claim 2, said means to move the trough including a rotatable shaft above said trough, a link secured at one end to said shaft, a second link pivotally connected at one end to said first link and at its other end to said trough, whereby one complete revolution of said shaft will raise and lower the trough, and means to rotate said shaft.

4. The combination of elements defined in claim 2, said means to tilt the trough including a pin extending inwardly from the back of said enclosure, and a cam rod extending upwardly from the rear of said trough bent at an angle near its upper end, whereby as the trough is moved upwardly the bent portion of said rod will contact said pin and tilt the trough.

5. A ball dispensing machine comprising, a trough to receive and dispense balls, a rotatable shaft, means connecting said shaft with said trough so that one revolution of the shaft will move the trough to dispensing position and back to receiving position, a cam on said shaft, a spring arm having one end thereof adapted to follow the contour of said shaft, a switch connected with said arm adapted to be closed and opened when the end of said arm reaches certain predetermined points on said cam, the switch when closed causing a rotation of said shaft, and means to initially start rotation of said shaft.

6. The combination of elements defined in claim 5, wherein said last named means includes a normally open switch so arranged in the circuit that a manual closing thereof will start a rotation of the shaft and will remain closed until the first named switch is closed by rotation of said cam, and means to thereafter open the second named switch.

7. The combination of elements defined in claim 5, said last named means including a normally open switch, and means to open said last named switch after the first switch has been closed by rotation of said cam.

8. The combination of elements defined in claim 5, said last named means including a normally open switch, means to open said last named switch after the first switch has been closed by rotation of said cam including a solenoid having an arm extending therefrom, and means to energize said solenoid.

9. A ball dispensing machine comprising an enclosure having a front, back and sides, two openings in said enclosure, ball receiving means having one end thereof adjacent one of said openings to receive balls as they enter said opening, means to move said receiving means to the other of said openings, means to dispense said

balls through said other opening, and a spring arm movable in the path of incoming balls to prevent entrance thereof into said enclosure when said receiving means is not in receiving position.

FRED W. PREECE.
